DESCRIPTION

U.S. PATENT DOCUMENTS

FIG. 1 is a display screen or portion thereof with a transitional graphical user interface, showing a first image of the claimed design; and,

D466,128 S * 11/2002 Han D14/489
D480,401 S * 10/2003 Kahn D14/488
D593,580 S * 6/2009 Truelove D14/491
D619,617 S * 7/2010 Dunn D14/491
D683,361 S * 5/2013 Kocmick D14/491
D684,182 S * 6/2013 Phelan D14/489
D695,307 S * 12/2013 Wu D14/491
D738,919 S * 9/2015 Torres D14/493
D775,667 S * 1/2017 Vulk D14/492
D777,784 S 1/2017 Jitkoff et al.
D793,447 S 8/2017 Jitkoff et al.
D795,925 S * 8/2017 Mantzke D14/491
D831,069 S 10/2018 Clapper et al.

FIG. 2 is a second image thereof.

The dot-dash broken lines in the drawings show a display screen or portion thereof and form no part of the claimed design.

The appearance of the transitional image sequentially transitions between the views of FIGS. 1-2. The process or period in which an image transitions to another forms no part of the claimed design.
